GRIPPING TOOL

Anthony M. Oliveri, Chicago, Ill., assignor to General Cement Mfg. Co., Rockford, Ill., a corporation of Illinois

Application March 10, 1948, Serial No. 13,968

20 Claims. (Cl. 294—64)

1

This invention relates to a gripping tool, and more particularly to a tool for gripping radio tubes for the purpose of extracting them from or inserting them into a socket.

This application is a continuation in part of my application entitled "Radio Tube Extractor," filed May 9, 1947, as Serial No. 747,083, now abandoned.

One feature of the invention is to provide a novel and improved gripping tool; a further feature of the invention is to provide a tool for gripping radio tubes or other elements with a pneumatic and frictional grip, together with apparatus operable to loosen the grip of the tool on the element; still another feature of this invention is to provide a tool for gripping a radio tube or other element with a pneumatic and frictional grip together with selectively operable apparatus for opening a valve to loosen said pneumatic grip and to exert pressure against said element to loosen the frictional grip of the tool on the element; yet a further feature of the invention is to provide a gripping tool having an open ended grip-loosening member adapted to engage the end of the tube or other element about its center, said open end receiving without engaging any protuberance at the center of said end; still another feature of this invention is that it provides a gripping tool having a body member and a resilient gripping member in said body member, at least a portion of the walls of said resilient member being spaced from said body member to permit expansion of said resilient member.

Other features and advantages of this invention will become apparent from the following specification and from the drawings in which:

Fig. 1 is a side elevation of a tool constructed in accordance with the present invention;

Fig. 2 is a vertical cross sectional view taken on the line 2—2 of Fig. 1;

Fig. 3 is an enlarged sectional detail of a portion of the tool shown in Fig. 2;

Fig. 4 is a vertical cross sectional view of a modified form of a gripping tool;

Fig. 5 is a side elevation, partly in vertical cross section of a further modification of a gripping tool constructed in accordance with the invention;

Fig. 6 is an enlarged sectional detail of a portion of the tool illustrated in Fig. 4;

Fig. 7 is an enlarged sectional detail of a portion of the tool illustrated in Fig. 5;

Fig. 8 is a side elevation of another modified

2

form of gripping tool; showing the tool gripping a radio tube;

Fig. 9 is a vertical cross section taken on the line 9—9 of Fig. 8, the radio tube being shown in elevation;

Fig. 10 is a cross sectional view similar to Fig. 9 but with the parts in a different position;

Fig. 11 is an enlarged sectional detail of a portion of the tool shown in Fig. 9; and

Fig. 12 is a further enlarged sectional detail of a portion of the tool shown in Fig. 11 with the radio tube removed.

Referring now to the drawings, one form of the invention is illustrated in Figs. 1, 2, and 3. In these figures the reference character 11 designates generally the body portion of the tool. Said body may be constructed of metal or of any suitable insulating material if desired, such as hard rubber or other plastic. At one end the body portion 11 is formed with a handle portion 12 and at the other end with a bell-like chambered portion 13. This chambered portion has at its end an annular internally grooved rib 14. Positioned inside the chamber of the portion 13 is a resilient sleeve 15 of rubber or similar resilient material, said sleeve being formed with an annular rib 16 which is seated in the annular groove in the rib 14 to lock the sleeve in place within the chamber. The elongated body member 11 is formed with a longitudinal bore 17, this bore extending axially of the member 11 in the construction illustrated, and being enlarged at the upper portion of the body, as shown at 18. A tubular rod 19 is loosely positioned in the bore 17, and a push button member 20 is secured to the top of the rod and projects from the top of the body member 11, this push button being slidable in the enlarged portion 18 of the bore. As seen in Figs. 1 and 2 the push button is formed with a top annular flange 21. The shank of the member 20 is formed with a plurality of longitudinal grooves 22 whereby the enlarged portion 18 of the bore and the main body of the bore 17 are open to the atmosphere.

45 A coil spring 23 surrounds the upper portion of the push rod, being seated on a shoulder at the base of enlarged portion 18 of the bore 17, and bears against the bottom of the push button member 20, thereby biasing the rod 19 upwardly.

50 The upper portion of the rod 19 is provided with an orifice 24 and the lower end of the rod carries a cylindrical valve housing 25, the bottom wall of which provides a downwardly tapered valve seat as shown at 26 in Fig. 3 around the central aperture 27. A ball 28 in the housing 25

engages the valve seat 26 and acts as a check valve to close the aperture 27 in a manner to permit air to enter the housing 25 from below said housing, but to prevent flow of air downwardly from tube 19. An outer sleeve 29 is secured to the housing 25, and bearing on the top of said sleeve is a washer 30 of resilient material such as rubber or the like, said washer being slidably engaged with the lower portion of rod 19. The rod 19 is flanged above the washer 30 as shown at 31 to limit upward movement of the washer with respect to the rod.

The tool is operated by telescoping the resilient sleeve 15 over the end of a radio tube, or other element, a portion of the tube being received within the chamber 13. During this operation the air above the tube escapes upwardly past the ball 28, through the tubular rod 19, through the orifice 24 and out to the atmosphere through vent grooves 22. The spring 23 biases the rod upwardly so that the sleeve 29 bears against the washer 30 and seals the interior of the chamber 13 with respect to the bore 17. The radio tube or other element is now gripped by the tool, the sleeve 15 having secured a pneumatic and frictional grip upon the tube, and by virtue of this gripping action of the tool the tube may be lifted out of its socket. To loosen the grip on the tube thereafter the push button 20 is pushed downwardly, which relieves pressure of spring 23 on the washer 30, permitting air from the atmosphere to enter the chamber from the bore 17 past said washer. If the radio tube is of the type having an upwardly projecting central tip or protuberance, depression of the valve housing 25 causes the ball 28 to be lifted upwardly off its seat into abutment with the bottom of the rod 19 by engagement with said projecting tip, thereby providing a second means for permitting air from the atmosphere to enter the chamber and providing a means for exerting additional downward pressure on the tube to push it towards the lower chamber opening, the main pressure in this regard being exerted by the member 29 which engages the end of the tube around the projecting tip.

As will be obvious the tool may be utilized for inserting a radio tube or other element into its socket or mounting apparatus as well as for removing such tubes or other elements.

Another form of my invention is illustrated in Fig. 4 wherein the tool comprises a body member 41 having an axial bore 42 in which is loosely positioned a rod 43. The axial bore has an upper enlarged end portion 44 in which is mounted a coiled spring 45 which encircles the upper portion of the rod 43 and bears upwardly on a push button member 46 secured to the upper end of the rod. The rod carries at its lower end a valve housing 47 in which is secured a valve seat member 48 having a central orifice 49 on which is seated a ball 50. The body 41 is formed at its lower end with a chambered portion 51 for the reception of the tube or other element to be gripped, the top wall of said chamber being conical and being sealingly engaged by the conical top wall surface of the valve housing 47. An aperture 52 is formed in the top wall of the valve housing 47.

Within the chambered portion 51 is secured a resilient sleeve member 53 which is held in position by a depending outwardly flared annular flange 54 integral with the body member 41. The outwardly flaring flange is formed after the sleeve member 53 is inserted in the chamber during

the process of manufacture of the tool so that the sleeve is securely locked in position.

In operation, the tool is telescoped over a radio tube in the same manner as described in connection with Fig. 1, the chamber 51 being vented to the atmosphere through orifice 52 and through bore 42. To loosen the grip on the tube after it has been extracted from its socket, the push button 46 is depressed, thus disengaging the conical top wall surface of the valve housing 47 from the conical inner top wall surface of the chambered portion 51, allowing air to enter the chamber 51 from the bore 42.

In the embodiment of Fig. 5 the tool structure is the same as that of Fig. 4 except that the resilient sleeve 53 is locked in position by a locking ring 55 which presses the upper portion of the sleeve into an annular internal groove formed in the wall of the chambered portion 51'. The operation of the device illustrated in Fig. 5 is the same as that of Fig. 4.

A preferred embodiment of the invention is illustrated in Figs. 8-12, in this embodiment the tool being shown in actual operation as gripping a radio tube 60. In this preferred embodiment the tool comprises an elongated body member designated generally at 61 and preferably being formed of a suitable metal, as for example aluminum, though other materials, as, for example, rubber, might be used. The body member 61 has an upper portion 61a which forms a handle for the tool. A longitudinal bore 62 extends through the body member, this bore being axial of the body member in the construction illustrated, and having its upper portion enlarged to accommodate a coiled spring 63. The bore 62 opens at its lower end into a first enlarged chamber 64, a portion 64a of the wall of which forms a valve seat. This first chamber opens into a further enlarged lower second chamber 65 which is adapted to receive the end of the radio tube or other element to be gripped.

While if desired the lower portion of the body member may itself be formed of resilient material, in the construction illustrated a resilient gripping sleeve 66 is mounted in the second chamber 65. As best seen in Fig. 11 the sleeve 66 is held in the chamber 65 by means of a relatively thick annular rib 66a integral with the sleeve which seats in a relatively deep annular groove 65a in the chamber. This construction prevents the sleeve from being pulled from the chamber even in the event that considerable force is exerted to remove the tube from its socket. A portion of the walls of the sleeve are spaced from the chamber walls, the upper portion of the sleeve being spaced by means of the rib 66a and the lower portion of the sleeve being spaced by means of a plurality of annular saw-tooth ribs 66b, this construction permitting expansion of the sleeve by entry therein of a radio tube or similarly shaped element. An inwardly extending annular flange or rib 66c is formed on the bottom of the sleeve 66 to insure that a seal is obtained between the sleeve and the wall of the tube or other element to be gripped. In Fig. 12 this flange is shown in normal or unstressed condition, and in Fig. 11 the flange is deformed or flattened by the wall of the tube 60 to form an air-tight seal around said tube. The particular formation of the flange 66c permits easy entry of the tube into the sleeve, while the flange, when deformed by the walls of the tube, forms an air-tight seal and assists in frictionally gripping the tube.

A push rod 67 is slidable axially of the bore 62,

this push rod extending at one end from the body member 61 and terminating in an enlarged push button 68. The coiled spring 63 abuts against the bottom surface of the push button 68 and against the annular shoulder defining the lower end of the enlarged upper portion of the bore and forces the push rod 67 upwardly. A cup-shaped combination valve and push member 70 is mounted on the lower end of the push rod 67, this member 70 cooperating as a valve with the valve seat 64a above described to close the bore 62. The member 70 is of substantial depth and is open-ended so that it will cooperate with the tube as a push member and engage the end of the tube when the push rod is actuated. The open ended portion terminates in a slightly rounded portion as may be seen at 70a in Fig. 11 to form a seat adapted to engage the top of the tube, the open ended portion being adapted to receive without engagement a protuberance on the tube end, as for example, the protuberance 60a which extends from the center of the end of the tube 60. As may be seen in Figs. 9, 10 and 11 the push rod 67 is of smaller diameter than the smallest diameter of the bore 62, and similarly the valve member 70 is of smaller diameter than the diameter of the first chamber 64 so that when the valve is opened air is admitted from the atmosphere to the second chamber 65.

In Figs. 8 and 9 the tool is shown as gripping a radio tube 60 which has been lifted from its cooperating socket. In order to accomplish this lifting operation the tool is applied over the end of the tube 60, the end of the tube 60 entering the second chamber 65 and the resilient sleeve 66 securing a frictional and pneumatic grip on the walls of the tube 60. As the end of the tube is inserted into the chamber 65 the walls of the sleeve 66 expand to permit entry of the tube and air under pressure in the chamber is vented around the wall of the tube. The lip 66c provides a seal preventing the re-entry of air from the atmosphere.

When it is desired to loosen the grip of the tool on the tube the push button 68 is pushed to move the push rod and valve member 70 to the position shown in Fig. 10. This action moves the valve member 70 away from the valve seat 64a and admits air to the second chamber 65 through the bore 62. In addition, the open ended portion of the valve member 70 engages the end of the tube and pushes the tube outwardly to loosen the frictional grip of sleeve 66 on the tube. As may be seen from the drawings, the protuberance 60a enters the open ended portion of the valve member, and the valve member only engages the end of the tube about its center while the protuberance at the center is received within the valve member without engagement. Thus there is no danger that this protuberance, which is usually of glass, will be broken.

While I have shown and described certain embodiments of my invention, it is to be understood that it is capable of still further modifications. Changes, therefore, in the construction and arrangement may be made without departing from the spirit and scope of the invention as disclosed in the appended claims.

I claim:

1. An element gripping tool of the character described, comprising: an elongated body member formed with an elongated longitudinal bore having a chamber at one end adapted to receive therein at least a portion of an elongated element to be gripped, at least the inner side walls of said

chamber being resilient for gripping contact around the sides of the element to be gripped; a rod movable axially of said bore; and apparatus in said chamber movable by said rod endwise relative to the chamber to loosen the grip of said tool on said element.

2. An element gripping tool of the character described, comprising: an elongated body member formed with an elongated longitudinal bore having a chamber at one end adapted to receive therein at least a portion of an elongated element to be gripped, at least the inner side walls of said chamber being resilient for gripping contact around the sides of the element to be gripped; and a portion of the wall of said bore forming a valve seat; a rod movable axially of said bore; and a combination push and valve member cooperating as a valve member with said seat and as a push member contacting the adjacent end of the element being gripped, the member being movable by said rod endwise relative to the chamber to loosen the grip of said tool on said element.

3. An element gripping tool of the character described, comprising: an elongated body member formed with a longitudinal bore having a chamber at one end adapted to receive at least a portion of the element to be gripped, at least the inner side walls of said chamber being resilient for gripping contact with the element to be gripped; and a push rod slidable axially of said bore and extending into said chamber, at least the end portion of said rod which extends into said chamber being open-ended and being adapted to engage the end of said element about its center without engaging said end directly at its center to loosen the grip of said tool on said element.

4. A tool of the character described for gripping an element having a protuberance at one end, comprising: an elongated body member formed with a longitudinal bore having a chamber at one end adapted to receive said end of the element to be gripped, a portion of the wall of said chamber forming a valve seat; a resilient gripping sleeve in said chamber adapted to grip said element pneumatically and frictionally; a push rod slidable axially of said bore; and a valve member engaging said rod and cooperating with said seat to close said bore, said valve member being movable to loosen the grip of said gripping member on said element by opening said chamber to atmosphere through said bore and by exerting pressure against the end of said element, said valve member having an open end and being adapted to engage the end of said element and to receive without engagement the protuberance at said end.

5. A tool of the character described for gripping a radio tube having a protuberance at one end, comprising: an elongated body member formed with an axial bore having an enlarged chamber at one end adapted to receive the end of the tube to be gripped, a portion of the wall of said chamber forming a valve seat; a resilient gripping sleeve in said chamber adapted to grip said tube pneumatically and frictionally; a push rod slidable in said bore; and a valve member engaging said rod, said valve member comprising a cylindrical cupped body of substantial depth positioned with its open end facing said chamber, said valve member cooperating with said seat to close said bore, said valve member being movable to loosen the grip of said gripping member on said element by opening said chamber to atmosphere.

through said bore and by exerting pressure against the end of said tube, said valve member having the open end of its cupped body adapted to engage the end of said tube and receive without engagement the protuberance at said end.

6. A tool of the character described for gripping a radio tube having a protuberance at the center of one end, comprising: an elongated body member formed with a longitudinal bore having an enlarged first chamber a portion of the wall of which forms a valve seat, and having a further enlarged second chamber adapted to receive the end of the tube to be gripped; a resilient gripping sleeve in said second chamber adapted to grip said tube pneumatically and frictionally; a push rod slideable in said bore; and a valve member engaging said rod, said valve member comprising a cup shaped body of substantial depth positioned in said first chamber with its open end extending into said second chamber and facing the end of the tube entered in said second chamber, said valve member being of slightly smaller cross section than said first chamber and cooperating with said seat to close said valve bore, said valve member being movable to loosen the grip of said gripping member on said tube by opening said chamber to atmosphere through said bore and by exerting pressure against the end of said tube, said valve member having the open end of its cupped body adapted to engage the end of said tube about its center, and receive without engagement the protuberance at the center of said end.

7. An element gripping tool of the character described, comprising: an elongated body member formed with a longitudinal bore having an enlarged elongated chamber at one end adapted to receive therein at least a portion of an elongated element to be gripped; an elongated tubular resilient element gripping member in said chamber, at least a portion of the walls of said resilient member being spaced radially from the walls of said chamber to permit radial expansion of said member; a rod slideable axially of said bore; and apparatus in said chamber movable by said rod endwise relative to said chamber to loosen the grip of said gripping member on said element.

8. A radio tube gripping tool of the character described, comprising: an elongated body member formed with a longitudinal bore having an enlarged first chamber a portion of the wall of which forms a valve seat, and having a further enlarged second chamber adapted to receive the end of the tube to be gripped; a resilient gripping sleeve in said second chamber adapted to grip said tube pneumatically and frictionally, the walls of said resilient sleeve being ribbed to provide a portion spaced from the walls of said second chamber to permit radial expansion of said sleeve; a push rod slideable in said bore; a valve member on said rod, said valve member comprising a cup shaped body of substantial depth positioned in said first chamber with its open end extending into said second chamber, said valve member being of slightly smaller cross section than said first chamber and cooperating with said seat to close said bore, said valve member being movable to loosen the grip of said gripping member on said element by opening said chamber to atmosphere through said bore and by exerting pressure against the end of said tube, said valve member being so constructed and arranged that the open end of its cup-shaped body is adapted to engage the end of said tube about

5 its center, and receive the end of said tube without engaging a protuberance at the center of said end; and a spring normally maintaining said valve closed.

9. An element gripping tool of the character described, comprising: an elongated body member formed with an axial bore having a chamber at one end adapted to receive at least a portion of the element to be gripped; at least the inner side walls of said chamber being resilient for gripping contact with the element to be gripped; a rod member slideable axially of said bore; a check valve carried by said rod member and formed and arranged to allow air to flow only into said bore from said chamber; a second valve normally closed but selectively operative to establish communication between said chamber and said bore; and apparatus carried by said rod member for operating said second valve.

10. A radio tube gripping tool of the character described, comprising: an elongated body member formed with an axial bore having an enlarged chamber at one end adapted to receive at least a portion of the tube to be gripped; at least the inner side walls of said chamber being resilient for gripping contact with the element to be gripped; a hollow rod loosely mounted in said bore; a check valve carried by said rod in said chamber, said check valve being formed and arranged to admit air only from said chamber into said rod, said rod being formed at its upper portion with an aperture; a second valve carried by said rod adjacent the check valve and formed and arranged to cooperate with the inner surface of the chamber to seal the bore with respect to the chamber; and selectively operable apparatus carried by said rod member for releasing said second valve from sealing engagement with the surface of the chamber.

11. A radio tube gripping tool of the character described, comprising: an elongated body member formed with an axial bore having an enlarged chamber at one end adapted to receive at least a portion of the tube to be gripped; a rod member slideable axially of said bore; a check valve carried by said rod member in said chamber, said check valve being formed and arranged to admit air only from said chamber into said bore; a second valve normally closed but selectively operable to establish communication between said chamber and said bore; apparatus carried by said rod member for operating said second valve; a resilient inner sleeve in said chamber, the inner wall surface of said chamber being formed with an annular groove, and an annular rib carried by said sleeve and seated in said groove.

12. A radio tube gripping tool of the character described, comprising: an elongated body member formed with an axial bore having a chamber at one end adapted to receive at least a portion of the tube to be gripped; a rod member slideable axially of said bore; a check valve carried by said rod member in said chamber, said check valve being formed and arranged to admit air only from said chamber into said bore; a second valve normally closed but selectively operable to establish communication between said chamber and said bore; apparatus carried by said rod member for operating said second valve; a resilient inner sleeve in said chamber, the inner surface of said chamber being formed with an annular groove; and a locking ring engaging said resilient sleeve and pressing a portion thereof into said annular groove.

13. An element gripping tool comprising a body

member formed to provide a chamber adapted to receive at least a portion of the element to be gripped, at least the inner side walls of said chamber being resilient for gripping contact with the element to be gripped, whereby to grip said element pneumatically and frictionally, a check valve operable pneumatically by said air exhausted from said chamber upon entry therein of the element to be gripped, whereby to effect a pneumatic seal for said chamber when the element is positioned therein, and a manually operable valve for opening said chamber to the atmosphere independently of said check valve.

14. An element gripping tool comprising a body member formed to provide a chamber adapted to receive at least a portion of the element to be gripped, at least the inner side walls of said chamber being resilient for gripping contact with the element to be gripped, whereby to grip said element pneumatically and frictionally, a check valve operable pneumatically by the air exhausted from said chamber upon entry therein of the element to be gripped, whereby to effect a pneumatic seal for said chamber when the element is positioned therein, a manually operable ejector, movable in said chamber, and a valve for opening said chamber to the atmosphere independently of said check valve arranged to be operated by said ejector.

15. An element gripping tool comprising a body member formed to provide an elongated chamber adapted to receive at least a portion of an elongated element to be gripped, at least the inner side walls of said chamber being resilient for gripping contact around the sides of the element to be gripped, whereby to grip said element pneumatically and frictionally, a manually operable ejector, movable in said chamber endwise thereof to mechanically eject the element therefrom, and a valve for opening said chamber to the atmosphere arranged to be operated by said ejector to open position in the ejecting movement.

16. An element gripping tool comprising a body member formed to provide a chamber adapted to receive at least a portion of the element to be gripped, at least the inner side walls of said chamber being resilient for gripping contact with the element to be gripped, whereby to grip said element pneumatically and frictionally, a manually operable ejector movable in said chamber, and a valve for opening said chamber to the atmosphere arranged to be operated by said ejector, said valve being so arranged that it is opened prior to engagement of the element by the ejector.

17. An element gripping tool for gripping glass tubes, such as radio tubes, having a protuberance on the outer end, comprising a body member formed to provide a chamber adapted to receive at least a portion of the tube to be gripped, at least the inner side walls of said chamber being resilient for gripping contact with the tube to be gripped, whereby to grip said tube pneumatically and frictionally, a manually operable ejector, movable in said chamber, that is cup-shaped so as to be engageable with the outer end of the tube around and out of engagement with

said protuberance, and a valve for opening said chamber to the atmosphere arranged to be operated by said ejector.

18. An element gripping tool for gripping glass tubes, such as radio tubes, having a protuberance on the outer end, comprising a body member formed to provide a chamber adapted to receive at least a portion of the tube to be gripped, at least the inner side walls of said chamber being resilient for gripping contact with the tube to be gripped, whereby to grip said tube frictionally, and a manually operable ejector, movable in said chamber, that is cup-shaped so as to be engageable with the outer end of the tube around and out of engagement with said protuberance.

19. An element gripping tool for gripping glass tubes, such as radio tubes, having a protuberance on the outer end, comprising a body member formed to provide a chamber adapted to receive at least a portion of the tube to be gripped, at least the inner side walls of said chamber being resilient for gripping contact with the tube to be gripped, whereby to grip said tube pneumatically and frictionally, a manually operable ejector, movable in said chamber, that is cup-shaped so as to be engageable with the outer end of the tube around and out of engagement with said protuberance, and a check valve operable pneumatically by the air exhausted from said chamber upon entry of a tube therein, whereby to effect a pneumatic seal for said chamber.

20. An element gripping tool for gripping glass tubes, such as radio tubes, having a protuberance on the outer end, comprising a body member formed to provide a chamber adapted to receive at least a portion of the tube to be gripped, at least the inner side walls of said chamber being resilient for gripping contact with the tube to be gripped, whereby to grip said tube pneumatically and frictionally, a manually operable ejector, movable in said chamber, that is cup-shaped so as to be engageable with the outer end of the tube around and out of engagement with said protuberance, and a check valve operable pneumatically by the air exhausted from said chamber upon entry of a tube therein, whereby to effect a pneumatic seal for said chamber, said check valve being carried by said ejector and arranged so as to be unseated by engagement therewith of the protuberance in the ejecting movement of said ejector.
